JAMES HARTNESS, OF SPRINGFIELD, VERMONT.

TURNING-TOOL.

1,020,494.

Specification of Letters Patent. Patented Mar. 19, 1912.

Application filed September 9, 1908. Serial No. 452,309.

To all whom it may concern:

Be it known that I, JAMES HARTNESS, of Springfield, in the county of Windsor and State of Vermont, have invented certain new and useful Improvements in Turning-Tools, of which the following is a specification.

This invention has relation to metal-turning tools, and has for its object to provide improvements therein, by which the work may be supported more effectively against the thrust of the cutter; the cutter may be fed relatively to the work by means coacting with the work, and the tool itself may be strengthened, rendered more accurate in operation, and its efficiency otherwise increased.

On the accompanying drawings, I have illustrated a tool embodying the invention.

Figure 1 represents a plan view of the same. Fig. 2 represents a side elevation of the same. Fig. 3 represents a front elevation of the same. Fig. 4 represents a rear elevation of the same. Fig. 5 represents a section on the line 5—5 of Fig. 2. Fig. 6 represents a section on the line 6—6 of Fig. 2. Fig. 7 shows the work-rests arranged at an angle to assist the feeding of the tool relatively to the work. Fig. 8 shows the engagement of one of the work-rests with the work.

I have illustrated the invention in connection with a turning tool having a cutter embodying the invention illustrated in my co-pending application, Serial No. 406,588, filed December 16, 1907, in which the cutter is formed as a wedge so that its inner and outer faces will receive substantially an equal pressure from the chip and the face of the work. Although I prefer to embody the invention in a tool of this character, nevertheless it will be understood that the various features of the invention may be utilized in connection with other forms of tool.

Upon the drawings, the tool is illustrated as consisting of a body or frame provided with a base member 20, which is adapted to be secured to the slide of a lathe, and a standard 21 rising from said base member at one end thereof. The standard is provided with an aperture 22 through which the work may pass. To the face of the upright or standard are pivoted what may be termed two carriers 23 and 24, the former of which receives and supports the work rests and the other of which receives and supports the cutter. The carrier 23 is pivoted upon a stud

or pin 25 which projects forward from the standard or upright near the base, as illustrated in Fig. 2, and the carrier 24 is similarly pivoted upon a stud or pin 26. To prevent these pins from springing or bending apart under pressure, they are connected by a link 27 which is apertured to receive them, and which is removably secured to the face of the standard by a screw 28. As an incident of construction, the carriers 23 and 24 are socketed to receive the semi-circular ends of the link or tie-plate 27. The carrier 23 and the carrier 24 are cut away at their upper ends so that they may overlap, as shown in Figs. 1 and 2, and the carrier 24 has a shoulder 29 which is adapted to engage a complementary shoulder 30 on the carrier 23. Said carriers are moved toward and from each other by a double eccentric 31 formed on the end of a shaft 32 which is journaled in the upright or standard 21. The outer member of the eccentric is indicated at 31^a and it is located in an aperture 32 in the carrier 24. The other member 31^b of the eccentric is located in an aperture 33 in the carrier 23 and engages one wall thereof, so that, when the handle 134 on the end of the shaft 32 is rocked, the two carriers will be drawn and locked closely together so as to hold the instrumentalities respectively supported by them in proper relation to the work.

The cutter is not essentially dissimilar from those described in my application hereinbefore referred to. It consists of an elongated bar or shank 34 placed in a groove or socket 135 formed in the side of the carrier 24. The operative end 35 of the cutter is wedge-shaped, so that its inner face may rest flatly against the face of the work. The cutting edge of the cutter is coincident with the corner of the shank or bar 34, and said corner is pivoted or fulcrumed in an angle formed by ribs or flanges or stops 36 in the upper wall of the groove 35. The lower side or edge of the bar is convexly curved and is supported upon pins 37, 38 which are adjustable by screws 39, 40, respectively, introduced into the carrier 24. The said corner of the bar or shank is held in its fulcrum by pins or members 41, 41, (see Fig. 2). These pins are arranged adjacent the ribs or flanges 36 and they are forced against the shank of the cutter by a shaft 43 having cams or eccentrics 44 which engage the outer ends of the pins. The shaft is provided with a handle 45 by which it may be rocked. The

cutter may be rocked about its fulcrumming point to cause the cutter to make its initial cut into the work or for other purposes by means of a slide 46. This slide is illustrated 5 as cylindrical, and it is placed in a transverse aperture in the carrier 24. At its end, it is provided with a transverse groove or recess 47 to receive the lower side or edge of the shank or bar 34. The slide is reciprocated 10 by a shaft 48 which has a rib or tooth 49 entering a transverse groove in the slide 46. The shaft 48 is arranged substantially parallel with the cutter bar and it is provided with a handle 50 by which it may be oscillated. By rocking the handle 50, the slide 15 46 may be moved in one direction or the other so as to vary the angular position of the inner face of the cutter or that face which rests against the work.

20 For the purpose of longitudinally adjusting the cutter and holding it against outward movement, I employ a cylindrical bar 51 which is arranged above the cutter and which is inserted in a socket in the side of 25 the carrier 24. The inner end of the bar is threaded so as to engage threads formed interiorly on the socket. The bar 51 has a collar 52, and, between this collar and a second collar 53 which is screwed in place 30 and then secured by a set screw 54, there is a block 55. The said block has a curved rib 56 which may be engaged in any one of a series of notches 57 in the upper edge of the cutter bar. By rocking the block 55 to an abnormal 35 position, the rib 56 may be disengaged from the notch 57 so as to permit the removal of the cutter bar. The block may be adjusted longitudinally of the cutter by rotating the bar 51 on which it is loosely 40 mounted, the rotation of said bar being effected by a handle 58 pivoted thereto and having a milled head 59. Threaded into the block are two stop-screws 60, 61; either of which may be brought into alinement with 45 the sides of the carrier so as to limit the inward movement of the block and accurately position the cutter with respect to the work. I have stated that the block 55 is loosely 50 mounted on the bar 51 and I mean that it is capable of rotating around the bar although it is held frictionally between the collars 52 and 53.

55 On the carrier 23, as previously stated, are supported the work-rests. These work-rests are arranged to engage the periphery of the turned portion of the work and also the face or shoulder on the work from which the metal is being removed by the cutter. The 60 rests consist of rotatable members whose end faces engage the periphery of the turned portion of the work and whose peripheries (although not necessarily for some purposes) engage the face or shoulder of the work, the axes of rotation of said rests being approximately radial to a line coincident

with the axis of the work. These members may be formed in any one of a variety of ways. I have illustrated them as consisting of disks 62 which are formed by flanges at the ends of the shafts or spindles 63. These 70 spindles are rotatably mounted in socket members 64. Each socket member is sleeve-like in construction, having one end open to receive the spindle and having at the other end an angular boss 65 through which a 75 screw 66 is passed. Each sleeve or socket member is exteriorly threaded and is inserted in a partially threaded aperture in the carrier 23, and it may be adjusted toward and from the work. The two sleeves or 80 socket members are arranged at an angle to each other, one opposite to the end of the cutter so as to resist the thrust of the work directly away from the cutter, and the other at a point between the first-mentioned sleeve 85 and the cutter so that the rest will bear upon the top of the work and resist its tendency to spring upward. Each of the socket members may be locked in position by a pin 67. These pins are arranged at an angle to each other, 90 as shown in Fig. 2, and against their ends rests a plate 68 with which is engaged a shoulder on a screw 69 passed into a threaded aperture in the side of the carrier 23. By means of this screw 69, the pins 67 may be 95 forced tightly against the socket members.

In the socket members are one or more washers or wearing disks 70, against which the ends of the spindles 63 bear, said washers or disks being interposed between the 100 spindles and the ends of the screws 66. Said screws may be adjusted by rotating them so as to vary the position of the work-rests and may be locked after adjustment by lock-nuts 71, 72.

105 The socket members, as shown in Fig. 5, are slightly inclined longitudinally of the axis of the work or to a line coincident therewith, so that the faces of the rests, if they were flat, would be at a slight acute 110 angle to the axis of the work. The end faces of the work-rests, however, are beveled so that the engagement of each face with the work is all on one side of the axis of the work-rest. This arrangement provides that the engagement of the rests with the periphery of the turned work shall partake of both the nature of a rolling contact and a sliding contact. This decreases the frictional engagement between the work-rests and the work, and at the same time prevents the entry of chips and cuttings or other foreign matter between them. The peripheries of the work-rests preferably engage the shoulder or face of the work, as 115 illustrated in Figs. 6 and 7.

120 As previously indicated, I may utilize the work-rests in effecting a relative movement of the tool and the work, or assisting in holding the cutter against the work. To do this, 125

I so arrange the socket members 64 that their axes are also at a tangent to a circle circumscribed about the axis of the work, as illustrated in Figs. 7 and 8.

Preferably the periphery of the rest is brought against the face of the work, as shown in Fig. 8, so that as the work rotates in the direction of the arrow *a*, it effects the rotation of the work-rest in the direction of the arrow *b*. This rotation of the work-rest tends to feed the work relatively to the tool or the tool relatively to the work, and this tendency toward effecting a relative movement of the parts maintains the engagement 15 between the work-rest and the face of the work. With this arrangement, the line of engagement between the face of the work-rests and the periphery of the work would be at a tangent to a circle circumscribed 20 about the axis of said work-rest, and at an angle to the work so that the rotation of the rest will feed the work forward.

The provision of the work-rests, the faces of which engage the work, permits the tool 25 to be so formed that the thrust of the work may be met by a rigid unyielding abutment.

Having thus explained the nature of my said invention, and described a way of constructing and using the same, although without attempting to set forth all of the forms 30 in which it may be made or all of the modes of its use, what I claim is:

1. In a metal-turning tool, a rotatable work-rest having a work-engaging face 35 transverse to its axis of rotation, and means for mounting said work-rest to rotate.

2. In a metal-turning tool, a cutter, a plurality of freely rotatable work-rests, and means for mounting them with their axes of 40 rotation substantially radially of a common axis.

3. In a metal-turning tool, a rotatable work-rest having at its end a work-engaging beveled face at an angle to its axis of rotation, and means for mounting said work-rest to rotate.

4. In a metal-turning tool, a rotatable work-rest having at its end a beveled work-engaging face, and a cylindrical peripheral work-engaging face adjacent the beveled end face.

5. In a metal-turning tool, a rotatable work-rest, and a support on which said work-rest is rotatively mounted, with its 55 axis inclined longitudinally of a line with which the axis of the work coincides when the tool is in operation and tangential to a circle circumscribed about said line, said rest having on its transverse end a work-engaging face.

6. In a metal-turning tool, a cutter, a cooperating work-rest, and a support for said rest on which said rest is rotatively mounted, said rest being inclined with respect to 60 a line with which the axis of the work coincides when the tool is in operation, and having at its end a conical work-engaging face.

7. In a metal-turning tool, a cutter and two rotatable work-rests having work-engaging faces on their ends, said cutter and

70

the axes of said work-rests being approximately radial of a common line, and means for supporting said cutter and said rests.

8. In a metal-turning tool, a cutter, a freely rotatable work-rest having at its end 75 a work-engaging face transverse to its axis of rotation, a socket member in which said rest is journaled, and means for supporting said socket member.

9. In a metal-turning tool, means for resisting the thrust of the cutter on the work, comprising a socket member, and a freely rotatable work-rest, consisting of a spindle journaled in said socket member and having a work-engaging face at its end, substantially transverse to its axis of rotation.

10. In a metal-turning tool, a pair of rotatable work-rests, consisting of rotary members whose axes are at an angle to each other and having work-engaging faces at 90 their converging ends transverse to their respective axes of rotation.

11. In a metal-turning tool, a pair of rotatable work-rests, consisting of rotary members whose axes are at an angle to each other, said members having work-engaging faces on their converging ends transverse to their respective axes of rotation, and a carrier having sockets in which said work-rests are journaled to rotate freely.

95

12. A turning tool, comprising a support, carriers pivoted on said support to move toward and from each other, a cutter on one of said carriers, one or more work-rests on the other of said carriers, and a member mounted on said support for engaging and moving both said carriers simultaneously toward or from each other.

100

13. A turning tool, comprising a support, carriers pivoted on said support, a cutter on one of said carriers, one or more work-rests on the other of said carriers, said carriers having free ends, and a rock-shaft journaled in said support and passed through apertures in said ends, said shaft having cams for swinging said supports about their pivots.

110

14. A turning tool, comprising a support, pins projecting from said support, a cutter carrier, a work-rest carrier, said carriers being pivoted upon said pins, a link or tie-plate connecting the ends of said pins, and a member on said support connected to the free ends of said carriers for simultaneously moving them in opposite directions.

115

15. In a metal-turning tool, a holder or carrier having a socket or recess, a cutter therein and having a shank with transverse notches, a bar projecting from said holder or carrier, and an abutment on said bar

120

125

130

movable transversely of the cutter into and out of engagement with said notched shank.

16. In a metal-turning tool, a holder or carrier having a socket or recess, a cutter therein having a shank with transverse notches, a bar projecting from said holder or carrier, an abutment on said bar movable transversely of said shank into and out of engagement with the notches in said shank, 10 and means by which said abutment is adjusted relatively to said holder or carrier.

17. In a metal-turning tool, a holder or carrier having a socket or recess, a cutter therein having a shank with a transverse 15 notch, a bar projecting from said holder or carrier, an abutment on said bar movable transversely of the shank into and out of engagement with said notch therein, and one or more adjustable stops for limiting 20 the adjustment of said abutment.

18. In a metal-turning tool, a holder or carrier having a cutter-receiving recess, a cutter therein comprising a bar or shank having a plurality of transverse notches, 25 and an abutment on said holder or carrier movable transversely of said shank to engage any one of said notches, whereby said cutter may be adjusted longitudinally into several predetermined positions and secured 30 in such positions.

19. In a metal-turning tool, a holder or carrier having a cutter-receiving recess, a cutter therein comprising a bar or shank having a plurality of transverse notches, an 35 abutment on said holder or carrier movable transversely relatively to said shank and adapted to engage any one of said notches, whereby said cutter may be adjusted longitudinally into several predetermined positions, 40 and means for adjusting said abutment in a direction longitudinal of said shank.

20. In a metal-turning tool, a body or frame, a carrier pivoted thereto, means for 45 moving said carrier relatively to said body, said carrier having a socket in one side, a cutter located in said socket and having transverse notches, and a member carried by said carrier and having a movable abutment to engage any one of said notches 50 whereby the cutter may be adjusted to a desired position and then be moved into work-engaging position.

21. In a metal-turning tool, a support, a 55 cutter comprising a bar or shank having a cutting edge extending endwise of its length,

a stop on said support taking over the side of said bar, a movable member to engage the other side of said bar, and a manually operated device to move said member and 60 clamp said bar against said stop.

22. In a metal-turning tool, a support, a cutter comprising a bar or shank having a longitudinally extending cutting edge, stops on said support taking over the side of said 65 bar, movable members on said support opposite said stops to clamp the bar thereagainst, and a manually operated device engaging said movable members to actuate them. 70

23. In a metal-turning tool, a cutter, and rotatable work-rests whose axes converge, each rest comprising a disk with a work-engaging face and a spindle or shank, adjustable socket members in which said 75 shanks are journaled, and means in said sockets engaging the ends of the said shanks and resisting the end thrust of said work-rests.

24. In a metal-turning tool, a support, ro- 80 tatable work-rests having end work-engaging faces and arranged with converging axes, socket members in which said work-rests are journaled arranged in recesses in said support, and means for clamping said 85 socket members.

25. In a metal-turning tool, a support, ro- 90 tatable work-rests having end work-engaging faces and arranged with converging axes, socket members in which said work-rests are journaled arranged in recesses in said support, members for engaging and 95 clamping said sockets, and means for operating said members simultaneously.

26. In a metal-turning tool, a body having 95 a work-receiving opening, a carrier pivoted to said body, a member for connecting the free end of said carrier with said body, a cutter seated on said carrier and having its operative end projecting into said opening, 100 said cutter consisting of an elongated bar having at its said operative end a cutting edge extending lengthwise of said bar, and means for securing said cutter bar on said carrier. 105

In testimony whereof I have affixed my signature, in presence of two witnesses.

JAMES HARTNESS.
